(57) CLAIM

I claim the ornamental design for a support for color sample for vehicles, as shown and described.

DESCRIPTION

FIG. 1 is a top view showing a first embodiment of my new design;

FIG. 2 is a right side view thereof;

FIG. 3 is a left side view thereof;

FIG. 4 is a front view thereof;

FIG. 5 is a rear view thereof; and

FIG. 6 is a bottom view thereof.

FIG. 7 is a top view showing a second embodiment of my new design;

FIG. 8 is a right side view thereof;

FIG. 9 is a left side view thereof;

FIG. 10 is a front view thereof;

FIG. 11 is a rear view thereof; and,

FIG. 12 is a bottom view thereof.
